UNITED STATES PATENT OFFICE.

LEWELL J. M. PETERSON, OF NEWARK, ILLINOIS.

MAGNETO-STARTER PAWL-TRIPPING DEVICE.

Application filed April 26, 1927. Serial No. 186,711.

The present invention relates to a novel and simple means for tripping the plunger which actuates the starter pawl of a magneto which is used upon tractors.

5 One of the important objects of the present invention is to provide a starter pawl tripping device which is remotely operable, thus obviating the necessity of having to lift up the hood of the tractor and manually actuate the 10 plunger associated with the impulse starter pawl of a magneto.

At the present time, considerable time and labor is lost whenever it becomes necessary to trip the plunger which is operatively associated with the starter pawl of a magneto on a tractor, and the present invention has for its 15 principal object to provide a simple and efficient means for positively tripping the plunger by merely pulling a wire which forms a part of the tripping mechanism and which wire extends outwardly through the hood of the tractor so that the same is at all times readily accessible.

A further object is to provide a device of 25 the above mentioned character which may be readily and easily attached to a magneto without necessitating any material alterations of the parts with which the same is associated.

A further object is to provide a tripping 30 device of the above mentioned character which is simple in construction, inexpensive, strong, and durable and further well adapted to the purpose for which it is designed.

Other objects and advantages of the invention 35 will become apparent from the following description taken in connection with the accompanying drawings.

In the accompanying drawings forming part of this application:

40 Figure 1 is a fragmentary perspective view of a front portion of the tractor showing the outwardly projecting end of the pull wire forming a part of the tripping device embodying my invention.

45 Figure 2 is a front elevation of the tripping device mounted on a magneto.

Figure 3 is a top plan view thereof.

Figure 4 is a side elevation, the pull wire 50 extending through the side of the hood of the tractor.

Figure 5 is a detail perspective view of the trip lever.

Figure 6 is a similar view of the stationary arm or bracket, and

Figure 7 is a detail perspective view of the 55 plunger tripping arm.

In the drawings wherein for the purpose of illustration is shown the preferred embodiment of my invention, the numeral 1 designates a magneto used on tractors and in the 60 present instance, the magneto is of the Splitdorf type. The impulse starter forming a part of the magneto is designated generally by the numeral 2 and adapted for cooperation with the notch 3 formed in the outer peripheral edge of the rotatable member 4 of the impulse starter is the pawl 5. This pawl is supported on the bracket 6 which is in the form of a plate and is secured on the side of the magneto and operatively associated with the 65 pawl for actuating the same is the vertically extending plunger 7, the same extending through the apertured lug 7' formed on the outer face of the bracket 6 at the upper edge portion thereof. 75

The parts thus far described are of the conventional construction and at the present time, it is necessary to lift up the hood A of the tractor in order to obtain access to the 80 upper end of the plunger 7 so that said plunger may be tripped whereby to move the pawl 5 into locking engagement with the notch 3 for the purpose well known in the art.

This entails the expenditure of considerable time and labor and frequently it is often 85 difficult to reach this plunger for tripping the pawl. The present invention has therefore been devised for the purpose of facilitating the tripping of the plunger at a point remote from the plunger. 90

My improved tripping device comprises a curved tripping arm 8, the curved end of which is slightly bent upwardly as is clearly shown in Figures 2, 4, and 7 of the drawings. The inner end of this tripping arm is enlarged as illustrated at 9 and a central opening 10 is formed in this enlarged portion. A series of slots are also formed in the central portion of the enlarged inner end 9 of the tripping arm 8 as indicated at 11 with reference more particularly to Figure 7 of the drawing. 100

The enlarged inner portion 9 of this tripping arm is adapted for disposition on the apertured lug 12 formed on the outer face 105 of the bracket or plate 6 at the upper edge thereof and adapted for cooperation with the tripping arm 8 is the trip lever 13, the inner

end thereof being enlarged as indicated at 14, and the enlarged inner end is formed with a central opening 15 which registers with the central opening 10 and the enlarged inner 5 end portion 14 of the trip lever 13 is disposed on top of the enlarged inner end 9 of the tripping arm 8 and a bolt 16 extends through the registering openings in the tripping arm and lever 8 and 13, respectively, as 10 well as through the apertured lug 12 formed on the outer face of the upper portion of the stationary bracket or plate 6.

A series of radially disposed tongues 17 depend downwardly from the outer edge of 15 the enlarged inner end 14 of the trip lever 13 and these tongues engage in the respective slots 11 provided therefor in the enlarged inner end portion 9 of the tripping arm 8 so that a rigid connection between the trip 20 lever and the arm will be provided thus permitting the two elements to operate simultaneously.

The means for actuating the trip lever and the tripping arm comprises an elongated pull 25 rod designated by the numeral 18. The inner end thereof is bent downwardly for disposition within the suitable opening 19 provided therefor in the outer end of the trip lever 13 as is clearly shown in Figure 4. 30 This pull wire extends laterally with respect to the trip lever 13 and is slideable through a suitable opening B provided therefor in the side of the hood A and the outer end of this pull rod terminates in a loop or eye 20, provides a handle whereby said rod may be easily 35 grasped for actuating the same.

Also forming an important part of the present invention is the bracket 21 which is in the form of a flat arm, the same tapering 40 gradually toward its outer end. The inner end of this arm is formed with an opening 22 which is adapted for registry with the opening in the apertured lug 12 and this arm is disposed below the lug, and the bolt 16 extends therethrough in the manner as clearly 45 shown in Figures 2 and 4 of the drawings. The arm or bracket 21 also extends laterally with respect to the trip lever and the tripping arm and for the purpose of preventing 50 the movement of the bracket 21 in a horizontal plane, the inner end of the arm or bracket is cut away to provide the finger 23, and the same extends through a suitable opening 24 provided therefor in the plate 55 or bracket 6.

A contractile coil spring 25 is secured at one end to the upwardly bent free end of the tripping arm 8, said end of the tripping arm being provided with an opening 26 to accommodate one end of the spring 25. The other 60 end of this spring is secured to the outer end of the stationary bracket 21 in a suitable opening 27 provided therefor and this is clearly shown in Figure 3 of the drawings.

65 The contractile coil spring 25 normally

holds the tripping arm 8 out of engagement with the upwardly projecting end of the plunger 7.

The operation of my improved tripping device may be briefly stated as follows: Normally the parts are arranged as shown in Figure 2 of the drawings and the pawl 5 is out of engagement with the notch 3 formed in the rotating member 4 of the impulse starter 2. The handle 20 is grasped and is pulled 75 outwardly and this will result in the interconnected tripping arm and trip lever to swing on the pivot provided by the bolt 16 so that the curved convex edge of the tripping arm will be brought into engagement 80 with the upwardly projecting end of the plunger 7 whereby to trip the plunger so that the pawl 5 will be moved into position for engagement with the notch 3, thus permitting 85 of the locking of the rotatable member 4 against further rotation until it comes to a certain tripping point within the impulse starter where at this point the impulse starter trips, thus sending a hot spark at the proper 90 time through the wires and the spark plugs of the internal combustion engine of the tractor whereby to facilitate the quick and easy starting of the motor, and to further prevent back firing.

As soon as the handle 20 is released, the 95 contractile coil spring 25 will automatically return the movable parts of the tripping device to their normal positions shown in Figure 2.

It will thus be seen from the foregoing 100 description, that I have provided a simple and efficient device for tripping the plunger which controls the starter pawl of a magneto, the device being at all times positive and efficient in its operation, and furthermore saving 105 considerable time and labor in actuating the tripping of the pawl. Also the simplicity of my device enables the same to be readily and easily associated with a magneto without necessitating any material alteration of the 110 parts of the magneto with which the tripping device is associated.

While I have shown the preferred embodiment 115 of my invention, it is to be understood that various changes in the size, shape and arrangement of parts may be resorted to without departing from the spirit of the invention and the scope of the appended claims.

Having thus described the invention, what I claim is:—

1. In a magneto starter pawl trip, wherein a plunger is operatively associated with the starter pawl for actuating the same, of a tripping arm pivotally mounted at one end on the magneto and normally out of engagement 125 with the plunger, an adjustable lever rigidly attached to the pivoted end of the tripping arm, a pull rod connected to the outer end of the lever for actuating the same at a remote point, and means for normally holding the 130

tripping arm out of engagement with the plunger, the plunger adapted to be tripped when the pull rod is actuated and the tripping arm is moved into engagement with the plunger.

2. In a magneto for trips wherein a plunger is operatively associated with the starter pawl for actuating the same, of a tripping arm pivotally mounted at one end on the magnet 10 neto normally out of engagement with the plunger, said arm being formed with apertures at its pivotal end, a lever adjustably attached to the tripping arm, said lever being

provided with lugs engageable with said openings for rigidly fixing the said arm and lever in proper association, and a pull rod connected to the outer end of the lever for actuating the same from a remote point, and means for normally holding the tripping arm out of engagement with the plunger, the plunger adapted to be tripped when the pull rod is actuated and the tripping arm is moved into engagement with the plunger.

In testimony whereof I affix my signature.

LEWELL J. M. PETERSON.
